UNITED STATES PATENT OFFICE.

REUBEN ECKSTEIN, OF NEW YORK, N. Y., ASSIGNOR, BY MESNE ASSIGNMENTS, TO NATIONAL CARBON COMPANY, INC., OF NEW YORK, N. Y., A CORPORATION OF NEW YORK.

FOCUSING LAMP.

Application filed June 6, 1921, Serial No. 475,241. Renewed July 29, 1927.

My invention relates to focusing lamps, and more particularly to focusing lamps of the kind carried in the pocket or held in the hand, and in which it is desirable to change 5 the focus by a simple adjustment, quickly and easily made.

Stated more specifically, my invention relates to the particular arrangement of the parts, whereby an incandescent lamp bulb 10 is associated with a lamp casing and a reflector and so arranged that the operator may at will readily shift the position of the lamp bulb relatively to the lamp casing and to the reflector, so as to vary the distribution 15 of the light from the bulb, this step being performed independently of the opening and closing of the circuit used for energizing and de-energizing the lamp bulb.

Reference is made to the accompanying 20 drawing forming a part of this specification, and in which like reference characters indicate like parts throughout the several figures.

Figure 1 is a central longitudinal section 25 through a lamp made in accordance with my invention, and shows the various movable parts as occupying their respective normal positions.

Figure 2 is a fragmentary section corresponding to the upper portion of Figure 1, 30 but showing certain parts as moved into abnormal positions, due to focusing of the lamp bulb relatively to the reflector.

Figure 3 is an elevation of some of the 35 parts appearing in Figures 1 and 2, but showing the parts in question as disassembled or separated.

A tubular casing 4 is made of fiber or other appropriate insulating material, and 40 is provided with a threaded end portion 5. Revolubly fitted upon this end portion 5 is a cap 6 which may be of metal, but is preferably made of insulating material, such as fiber. This cap is provided with a boss 7, 45 which engages a battery cell 8. A dry battery is well adapted for use in this connection.

A reflector 9 carries a cover glass or lens 10, secured thereupon by an annular cap 11. 50 The reflector 9 is provided with an annular portion 12, threaded externally, and carries an abutment or stop portion 13, having a general annular form and provided with a centrally disposed opening 14. The tubular

casing 4 is provided with an end portion 15, threaded internally to fit the annular portion 12 of the reflector 9.

Bearing against the annular portion 13 is a stout spiral compression spring 17, made of metal, preferably brass or steel. A fiber washer 18 engages the spring 17, and carries a metallic eyelet 19, extending through it centrally. Engaging the eyelet 19 is an electrode 20, constituting one terminal of the dry battery. The other terminal of the 65 battery is the metallic shell 8^a, shown more particularly at the lower left-hand portion of Figure 1.

A metallic lamp holder shell is shown at 21, and is made of sheet metal, so corrugated 70 as to be virtually threaded. This shell is connected with the spring 17, preferably by soldering, and is provided with an overhanging flange 22. The shell 21 extends loosely through a hole 23 in the washer 16 75 and is movable axially of the reflector through the opening 14. An incandescent lamp bulb 24 is provided with a stem 25 of conventional form, this stem being threaded and fitted into the shell 21 as a 80 lamp socket. The outer surface of the stem serves as one terminal of the lamp, and the other terminal, having the form of a metallic nipple, appears at 26.

The compression spring 17 is always under compression, its tendency being to increase the distance between the washers 16 and 18 until the flange 22 rests firmly against the adjacent portion of the washer 16. The washer 16 is stationary, being 90 pressed against the annular member 13. The washer 18, however, is movable, being under control of the position occupied from time to time by the battery, and this in turn being under control of the cap 6, which is 95 adjustable by hand.

Thus the operator, by grasping the casing 4 with one hand and turning the cap 6 with the other, can shift the position of the battery relatively to the casing, and by so 100 doing can within reasonable limits compress the spring 17 or cause it to flex to any desired extent. By doing this, the operator can cause the lamp bulb to protrude into the reflector as indicated in Figure 2, or 105 withdrawn into the position indicated in Figure 1, or to occupy any intermediate position. Thus the practical working focus

of the lamp is changed to any desired extent at the will of the operator, by merely turning the cap 6 back and forth.

I will next describe the electrical connections used in my lamp. The battery casing 8^a is engaged by a strip 27 of metal, this strip having a portion 28 bent outwardly through an opening 29 in the casing 4, and clinched. Another strip 30 of metal is insulated from the battery casing 8^a, as shown, and is provided with an end portion 31, bent outwardly through the opening 29, and clinched. The two portions 28 and 31 are properly formed and arranged to serve as contact members. A leaf spring 32, made of metal and serving as a contact member, is connected with and controllable by a thumb button 33, and therewith is slidably mounted upon a stationary guard strip 34, carried by the casing 4. The operator, by placing his thumb on the button 33 and sliding the same back and forth, can so shift the contact spring 32 as to bring it into engagement with both contact members 28 and 31, or with only the contact member 28. The upper end portion 30^a of the strip 30 is preferably bare, as shown, and is in engagement with the metallic washer 16, being preferably though not necessarily soldered, brazed or welded thereto.

With the button 33 in its position indicated in Figure 1, the circuit is open; to close the circuit, the button is merely slid downwardly a little according to this figure, so as to bring the contact spring 32 into engagement with the contact member 31. The circuit is thus completed, as follows: battery casing 8^a, strip 27, contact member 28, contact spring 32, contact member 31, strip 30, washer 16, spring 17, shell 21, lamp terminal 25, lamp 24, lamp terminal 26, eyelet 19, battery terminal 20, through battery 8 to battery casing 8^a.

Figure 3 indicates the manner in which various parts are assembled; the inter-relations of the parts being obvious.

I invite special attention to the fact that the focusing of my improved lamp from time to time at the will of the operator is accomplished in such manner as not to disturb the contact of any of the electrical connections; and particularly that the circuit can not be either opened or closed by the movement of the lamp bulb relatively to the reflector, in focusing the lamp or otherwise varying the distribution of the light, incidental to adjustment of the position of the lamp bulb relatively to other parts. The disconnection of the flange 22 from the adjacent portion 55 of the metallic washer 16 can have no effect upon the condition of the circuit, which is controlled absolutely from the position of the button 33, as above explained.

I do not limit myself to the precise mechanism shown, as variations may be made

therein without departing from my invention, the scope of which is commensurate with my claims.

Neither do I limit myself to the use of my focusing lamp for any particular purpose, nor to its construction as of any special materials. Generally speaking I prefer that all parts of the device be made of standard material, or at least material readily standardized.

Having thus described my invention, what I claim as new and desire to secure by Letters Patent is as follows:

1. In a focusing lamp the combination with a lamp casing and a reflector carried thereby, of a lamp bulb located within said casing and movable bodily in relation to said reflector, a battery located within said lamp casing and movable relatively thereto, said battery being connected with said lamp bulb so as to move said lamp bulb relatively to said reflector whenever said battery is moved relatively to said lamp casing, said battery being connected with said lamp bulb by a circuit under control of the operator for the purpose of causing said battery to energize said lamp bulb, and an adjustable member of insulating material controllable at the will of the operator for adjusting the position of said battery relatively to said casing.

2. In a focusing lamp the combination with a lamp casing and a reflector carried thereby, of a battery located within said lamp casing and movable bodily in relation to said casing and said reflector, and a lamp bulb connected with said battery and energized thereby under control of the operator, said lamp bulb being disposed adjacent said reflector and movable bodily in relation thereto in response to movements of said battery relatively to said casing, and a cap of insulating material adjustable on said casing controllable at the will of the operator for moving said battery relatively to said lamp casing.

3. In a focusing lamp the combination, with a lamp casing and a reflector carried thereby and normally stationary in relation thereto, of a lamp bulb carried by said casing and extending into said reflector in order to cause said reflector to vary the distribution of the light from said lamp bulb, a stop member carried by said casing, a spring located within said casing and bearing against said stop member, a lamp holder connected with said spring and movable relatively to said stop member as said spring is flexed, a battery housed within said casing and movable with said lamp holder relatively to said stop member so as to flex said spring, and a circuit including said battery and said lamp bulb and holder, said circuit being controllable by the operator for causing said battery to energize said lamp bulb.

4. In a focusing hand lamp the combina-

tion of a reflector, an abutment member carried by and coaxial with said reflector, a compression spring bearing against said abutment member, a lamp bulb having a 5 pair of terminals one of which is in circuit with said spring, and a battery provided with a pair of terminals one of which is in circuit with said spring, the other being electrically connected with a terminal of 10 said lamp bulb, by a circuit under control of the operator.

5. In a focusing flashlight, the combination of a casing, a battery therein, a lamp in circuit with said battery, a reflector mounted 15 on and providing a closure for one end of said casing, said reflector having an apertured portion providing an abutment, a lamp holder adjustable axially through such aperture, a compression spring bearing 20 against said abutment and expandible to move said lamp holder, and a closure cap for the other end of said casing, said cap being adjustable to move said lamp holder.

6. In a flashlight, the combination of a 25 tubular casing, a battery therein, a lamp in

circuit with said battery, a reflector threaded to said casing and constituting the head of said flashlight, said reflector carrying a portion substantially closing the head end of said casing, a cover glass secured to said reflector, a lamp holder adjustable axially of said reflector, and a cap closing the other end of said casing and bearing against said battery.

7. In a flashlight, the combination of a 35 tubular casing of insulating material, a battery therein, a lamp in circuit with said battery, a flaring reflector constituting the head end of said flashlight and having an externally threaded portion fitting into and 40 threaded to said casing, said reflector comprising an apertured portion forming an abutment substantially closing one end of said casing, a lamp holder adjustable through such aperture axially of said reflector, and 45 a cap of insulating material closing the other end of said casing and bearing against said battery.

REUBEN ECKSTEIN.
